UNITED STATES PATENT OFFICE.

LEWIS J. BAZZONI, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

PUNCHING-MACHINE.

1,191,939.

Specification of Letters Patent. Patented July 25, 1916.

Application filed August 29, 1912. Serial No. 717,747.

To all whom it may concern:

Be it known that I, LEWIS J. BAZZONI, a citizen of the United States, residing at Swampscott, in the county of Essex and

5 State of Massachusetts, have invented certain Improvements in Punching-Machines, of which the following description, in connection with the accompanying drawings, is a specification, like reference characters on 10 the drawings indicating like parts in the several figures.

This invention relates to the formation of perforations or indentations in a piece of material and the application of a coating 15 or other substance to the edges of such perforations or indentations, and is herein illustrated in connection with a machine for forming perforations in pieces of leather and for inking the edges of such perforations.

20 In the manufacture of boots and shoes it is customary to ornament the toe tips and certain other portions of the upper by forming in the margin thereof a row of perforations. Inasmuch, however, as the dye with

25 which the leather is colored seldom permeates the leather completely, the edges of the perforations are usually of a color different from that of the surface of the leather. For example, when black leather is perforated there is commonly exposed a stratum

30 of lighter color. Hitherto, this stratum has been colored by dipping the piece of leather into ink. The dipping process necessitates the subsequent removal of the surplus ink 35 which adheres to the surface of the leather, and this removal has been accomplished by wiping off the surplus ink with a piece of cloth. The coloring of the edges of the perforations has thus involved a slow process, 40 wasteful both of time and of ink or other coating substance.

The general object of the present invention is to do away with the hand operations outlined above.

45 To this end one feature of the invention consists of a support for a perforated piece of stock, a carrier for a coating substance, and means for causing said carrier to enter said perforation. Each carrier for the coating substance is so formed and arranged as 50 to measure a predetermined quantity of

coating substance from the container and to transfer such predetermined quantity to the stock. Conveniently the carrier may be the 55 punch itself.

Another feature of the invention therefore consists of a support for a piece of stock, means for perforating said piece, and means for applying a coating substance to the edge of the perforation. It is very desirable, particularly when parts of shoes are being operated upon, that the application of coating substance be confined to the edge of the 60 perforation so that none of the substance may escape upon the surface of the leather. 65

Another feature of the invention, then, consists of a support for a perforated piece of stock, means for applying pressure to the stock about the edge of the perforation, and means for applying a coating substance 70 to said edge during the continuance of said pressure. Here again, if desired, the punch itself may serve as a conductor or carrier for the coating substance so that, as stated above, the perforating and the coating may be 75 accomplished in a single operation.

These and other features of the invention, including certain details of construction and combinations of parts, will be described in connection with an illustrative machine and 80 pointed out in the appended claims.

Referring now to the accompanying drawings, Figure 1 is a front elevation of a machine in which the present invention is embodied, a part of the ink container being 85 broken away to expose the punches; Fig. 2 is an end elevation of the machine viewed from the right of Fig. 1, and Fig. 3 is a cross section on the line 3—3 of Fig. 1, the parts being shown in the position occupied during 90 the inking of the edge of the perforation.

Fast to the uprights 1 of the frame of the machine are brackets 5 in the grooves of which ribs 7 of the ink container 9 are slideable so that said container may readily be 95 removed when desired. Mounted in vertical guideways 11 in the uprights 1 are slides 13. Fast to the upper ends of the slides is a cross head 15, and similarly fast to the lower ends is a bar 17. The cross head, slides and bar 100 thus form a frame which is mounted for reciprocation in the uprights 1. Carried by

the cross head 15 and extending through aligned bores in the ink container 9 are a plurality of punches 19 having recesses or pockets 21. Normally the punches are in the position illustrated in Fig. 1 with their cutting ends within the wall of the ink container and their pockets in communication with said container. Each pocket 21 is so formed and arranged that it is cut off from communication with the container when it is moved to transfer the coating substance to the stock. A predetermined quantity of coating substance is thus measured and carried from the container, and no more than such predetermined quantity can be transferred at any one operating stroke of the punch.

The table or work support 23 is provided with sockets or bores 25 to receive the punches and has at its ends slideways which movably embrace the slides 13 so that said support may be raised and lowered relatively to said slides. The purpose of raising the support is to force the stock tightly against the bottom of the ink container prior to the downward movement of the punches so that when the punches have reached the position shown in Fig. 3 the ink in the recesses or pockets 9 may be effectually prevented from reaching the surface of the leather. These relative movements of the work support and the cross head are brought about by the following mechanism: Surrounding an eccentric 27 which is fast to the shaft 29 is an eccentric strap 31 to which is fast an arm 33. A pivot 35 connects the arm 33 with a second arm 37 the hub 39 of which is fast to a rock shaft 41 mounted in the frame of the machine and held from longitudinal movement by collars 43. Yielding upward movement is imparted to the work support 23 from the rock shaft 41 through a spring 45 one end of which bears against a plate supported by an adjusting screw 47 threaded through a portion of an extension 49 of an arm 51 the hub of which is fast to the rock shaft 41. The other end of the spring bears against the bottom of a socket formed in a second extension 53 of a second arm 55, said second arm being pivoted at 57 to the arm 51 and having at its outer end an enlarged portion 58 provided with an elongated eye 59 which cooperates with a roll 61 the pintle of which is mounted in ears 63 formed on the work support 23. Thus when the shaft 29 is rotated the effect of the first part of the rotation is to rock the shaft 41 in a clockwise direction and thereby force the work upwardly against the bottom of the ink container 9, the pressure of the work support against the work being progressively increased by the compression of the spring 45 until the shaft 29 has been moved through 180°.

65 In order to move the cross head 15 and

the punches 19 downwardly as soon as the work support has pressed the work against the bottom of the container, the collars 43 have formed on their lower portions yokes 65 which coöperate with projections 67 on the hubs 69 of arms 71. The hubs are pivoted on stud shafts 73, and the arms have at their outer ends enlarged portions 75 provided with elongated eyes 77 to receive rolls 79 which are rotatable on stud shafts carried by the bar 17. The shaft 29 carries a pulley 81 by which it may be driven, and preferably a one-revolution clutch, not shown, of any approved type is provided to cause the machine to come to rest automatically in the position shown in Figs. 1 and 2.

As has been stated, the work support is provided with bores to receive the punches, and these bores open at their lower ends into a chamber 83 which receives the "pills" 85 produced by the punching operation. The punches may be of any suitable form and in the illustrated machine are shown as being provided with V-shaped notches at their lower ends to facilitate the production of a clean perforation.

In order to maintain a uniform level of ink in the container 9 a passage 85 leads into a cup 87 into which extends the neck of an inverted bottle 89 or other receptacle for ink.

The operation of the machine is as follows: With the parts of the machine in the position shown in Figs. 1 and 2 a piece of leather is placed upon the work support 23 and the driving shaft 1 is caused to make a revolution. The effect of the first part of the revolution is to raise the work support and thereby press the work against the bottom of the ink container 9. About the time this has been accomplished the yokes 65 engage the projections 67 thereby rotating the arms 71 and pulling down the cross head 15 and the punches 19. Meanwhile the spring 45 has been compressed still further so that when the punches reach the position shown in Fig. 3, wherein the pockets have been moved from a position in the ink container into a position in which the ink is applied to the edges of the perforations, the work will be held very tightly and no ink can escape to the surface. The further rotation of the shaft 29 restores the parts to the position shown in Figs. 1 and 2.

The invention has been set forth in connection with a machine for applying ink to the smooth edges of the perforations made in a piece of leather by cylindrical punches, but it should be understood that neither the nature of the stock in which the perforations are made, nor the character of the edges or walls of the perforations, nor the substance which is applied is material to the invention.

Although in the illustrative machine the purpose of gripping the stock in the manner described prior to the punching opera-

- tion has been stated to be to prevent the ink from reaching the surface of the leather, it should be noted that it serves the further purpose of producing a clean perforation.
- 5 It should also be noted that the punches are at all times prevented from the slightest bending so that the perforations are perfectly true and uniformly located with reference to one another.
- 10 Throughout the claims the term "coating substance" will be used in referring to the substance which is applied, since it is evident that liquid, viscous, pasty, granulated and other suitable substances or materials 15 may be employed if desired.

Having thus described my invention, I claim as new and desire to secure by Letters Patent of the United States:

1. A machine of the class described, comprising in combination, means arranged to form a perforation in the stock, and means arranged to measure a predetermined quantity of fluid substance and to carry such predetermined quantity in such perforation.

25 2. A machine of the class described comprising in combination, means arranged to form a perforation in the stock, a reservoir for a fluid substance, and means arranged to measure a predetermined quantity of such substance and to transfer such predetermined quantity from said reservoir into such perforation.

3. A machine for operating upon a perforated piece of stock, comprising in combination, a support for the stock, a fluid-holding chamber, a carrier having an external fluid-receiving recess movable into the fluid in said chamber and movable into a perforation in the stock, and means arranged to 35 act with said carrier to confine the fluid in said recess until such fluid enters such perforation.

4. A machine for operating upon a perforated piece of stock, comprising in combination, a support for the stock, a fluid-holding chamber, a carrier having an external fluid-receiving recess movable into the fluid in said chamber and movable into a perforation in the stock, means arranged 50 to coact with said carrier to confine the fluid in said recess until such fluid enters such perforation, said means and said stock support being relatively movable to press the stock adjacent such perforation, and means arranged to cause such pressure.

5. A machine for operating upon a perforated piece of stock, comprising in combination, a support for the stock, a fluid-holding chamber above said support, a carrier having an external fluid-receiving recess movable into the fluid in said chamber and movable into a perforation in the stock, and means arranged to coact with said carrier to confine the fluid in said recess until such fluid enters such perforation, said carrier

being formed to close communication between said chamber and perforation when said recess is in register with said perforation.

6. A machine for operating upon a perforated piece of stock, comprising in combination, a support for the stock, a reservoir arranged to coact with said support to clamp the stock, said reservoir having an outlet port in its stock-engaging wall, a carrier arranged to coact with said port to close the same, said carrier having an external fluid-receiving recess arranged to enter the fluid in said reservoir, and means arranged to move said carrier and said recess into a perforation in the stock, said stock-engaging wall being arranged to confine the fluid in said recess until such fluid reaches such perforation. 70

7. A machine of the class described having, in combination, a container for a coating substance having a bore extending through a wall thereof, a punch provided with a pocket and mounted to reciprocate in said bore, said pocket being normally in communication with said container, a support for said piece of stock located adjacent said container, means for gripping the stock between the support and the container, and means for reciprocating the punch to perforate the stock and to cause the pocket to conduct coating substance to the edge of the perforation. 80

8. A machine of the class described, comprising a punch and die, a reservoir for fluid arranged above said die and having an outlet port in line with said die, said punch being arranged to slide in said port to control the discharge of fluid therethrough, means arranged to cause relative movement of said die and reservoir to clamp a piece of stock, and means arranged to operate said punch to perforate the stock, said punch having an external annular groove arranged to enter the fluid in said reservoir and to enter the perforation formed in the stock by said punch, said port and groove being arranged to transfer a predetermined quantity of fluid from said reservoir to the perforation in the stock. 100

9. A machine of the class described having, in combination, a container for a coating substance having a bore in one wall thereof, a punch having a pocket, means for reciprocating said punch in said bore, a support for the stock located adjacent said container, and means for moving said support toward said container to apply pressure to said stock prior to the operation of the punch. 110

10. A machine of the class described having, in combination, a container for a coating substance having a bore in one wall thereof, a punch having a pocket, means for reciprocating said punch in said bore, a sup- 120

port for the stock located adjacent said container, means for moving said support toward said container to apply pressure to said stock prior to the operation of the 5 punch, and means for increasing said pressure during said operation.

In testimony whereof I have signed my

name to this specification in the presence of two subscribing witnesses.
